UNITED STATES PATENT OFFICE.

EDWARD A. FIELD, OF CHICAGO, ILLINOIS, ASSIGNOR TO DANGEL-FIELD CO., OF CHICAGO, ILLINOIS.

WATER-TUBE BOILER.

Application filed April 27, 1927. Serial No. 186,927.

The main object of this invention is to provide an improved water tube boiler which is highly efficient, may be readily cleaned, has no baffle plates and no horizontal surfaces for the collection of soot and scale, and one in which the tubes are not likely to become clogged with scale or sediment.

A further object is to provide a structure having these advantages which is very economical in its parts and one in which the parts can be readily assembled and disassembled, particularly in the matter of tubes, as occasion may require.

Objects pertaining to details and economies of my invention will definitely appear from the description to follow. The invention is defined in the claims.

A structure embodying the features of my invention is clearly illustrated in the accompanying drawing in which:

Fig. 1 is a side elevation partially in central longitudinal section on line 1—1 of Figs. 2 and 3.

Fig. 2 is a transverse section on line 2—2 of Fig. 1.

Fig. 3 is a fragmentary plan view partially in horizontal section on line 3—3 of Fig. 1.

In the embodiment illustrated, I provide a base designated generally by the numeral 1 having an ash pit chamber 2 at the front and a smoke box chamber 3 at the rear. The grate 4 illustrated is of a standard type.

The outer shell designated generally by the numeral 5 and inner shell designated generally by the numeral 6 are arranged in spaced relation to provide a water chamber 7 surrounding the inner shell. This inner shell comprises downwardly diverging fire box wall portions 8 and vertically disposed combustion chamber side wall portions 9 connected by the outwardly inclined tube plate portions 10. The crown sheet portion 11 has a central horizontal portion 12.

A bridge wall plate 13 is arranged to project above the smoke box 3 providing a down passage 14 at the rear of the combustion chamber. The bridge wall 15 is formed of fire brick, the wall plate 13 being preferably slightly inclined and shouldered to receive and effectively support the brick. The tubes 16 are all vertically disposed and angled as illustrated. The top portions 17 of these tubes are disposed through the horizontal portion 12 of the crown sheet and at right angles thereto. The bottom portions 18 of these tubes are connected to the

tube plates 10 and disposed at right angles thereto.

This form of side walls of the inner shell provides an enlarged water space at the bottom extending the length of the boiler on both sides which insures an ample supply of water to keep the tubes filled at all times, and thus promoting rapid circulation through the tubes which prevents foaming and increases the efficiency of the structure.

The outer shell is provided with a plurality of plugs 19 in the top thereof and a plurality of plugs 20 in the side walls thereof, each plug being disposed in a centered relation relative to a group of the tubes, commonly a group of four, so that all of the tubes of the group are accessible through the one plug opening and the group of tubes cleaned through the single opening.

This results in economy of manufacture, as the tubes may be closely arranged, and they have no horizontal portions to collect soot and the like. The tubes are all readily accessible for cleaning.

The smoke pipe is connected to the smoke box 3 at 21. This arrangement enables dispensing with baffles and at the same time efficiency is maintained as the hot gases impinge not only the walls of the combustion chamber but the tubes arranged therein.

I have not attempted to illustrate or describe certain modifications or adaptations which I contemplate as I believe the disclosure made will enable those skilled in the art to embody or adapt my improvements as may be desired.

Having thus described my invention what I claim as new and desire to secure by Letters Patent is:

1. In a boiler, the combination of a base provided with an ash pit chamber at the front and a smoke box at the rear, an outer shell, an inner shell spaced therefrom to provide a water chamber surrounding the inner shell, said inner shell comprising downwardly diverging fire pot wall portions, vertical combustion chamber side wall portions connected to said fire pot wall portions by outwardly inclined tube plates, and a crown sheet having a horizontal central portion, a plurality of vertically disposed angled water tubes having top portions disposed at right angles to the horizontal portion of the crown sheet and bottom portions disposed at right angles to the said tube plates, and a bridge

- wall disposed at the rear of the fire box and providing a down passage at the rear of the combustion chamber communicating with said smoke box.
- 5 2. In a boiler, the combination of a base provided with an ash pit chamber at the front and a smoke box at the rear, an outer shell, an inner shell coacting therewith to provide a water chamber and extending over said
- 10 smoke box, a plurality of vertically disposed angled water tubes having their upper ends

connected to the crown sheet of the inner shell and their lower ends connected to the side walls thereof, said inner shell and said tubes being continued over said smoke box,¹⁵ and a bridge wall disposed at the rear of the firebox and providing a down passage at the rear of the combustion chamber communicating with said smoke box.

In witness whereof I have hereunto set my hand.

EDWARD A. FIELD.
